The ornamental design for an ice maker, as shown and described.

DESCRIPTION

FIG. 1 is a front, right, and top perspective view of an ice maker, showing my design.

FIG. 2 is a rear, left, and bottom perspective view of the ice maker in FIG. 1.

FIG. 3 is a front view of the ice maker in FIG. 1.

FIG. 4 is a rear view of the ice maker in FIG. 1.

FIG. 5 is a left side view of the ice maker in FIG. 1.

FIG. 6 is a right side view of the ice maker in FIG. 1.

FIG. 7 is a top view of the ice maker in FIG. 1.

FIG. 8 is a bottom view of the ice maker in FIG. 1.

FIG. 9 is another front, right, and top perspective view of the ice maker in FIG. 1 in a first state; and,

FIG. 10 is another front, right, and top perspective view of the ice maker in FIG. 1 in a second state.

The broken lines shown in the drawings are included for the purpose of illustrating portions of the ice maker that form no part of the claimed design.
